UNITED STATES PATENT OFFICE.

GEORGE S. ROBERTS, OF BEND, OREGON.

VALVE-SPRING-COMPRESSING MACHINE.

Application filed January 31, 1922. Serial No. 532,987.

To all whom it may concern:

Be it known that I, GEORGE S. ROBERTS, a citizen of the United States, and a resident of Bend, in the county of Deschutes and State of Oregon, have invented a new and Improved Valve-Spring-Compressing Machine, of which the following is a full, clear, and exact description.

This invention relates to improvements in spring compressing machines, particularly to that class of machines used in compressing the valve springs of internal combustion engines for the purpose of assembling or disassembling the valves for grinding or repairing, etc., an object of the invention being to provide a time and labor saving device of this character.

A further object is to provide an attachment for the machine in the form of a shim punch so that the same machine may be used either for compressing valve springs or for punching shims.

A still further object is to provide a machine of this character, which will be exceedingly simple and practical in construction, durable and efficient in use, which will occupy a comparatively small amount of space, and which can be economically manufactured.

With these and other objects in view, the invention consists in certain novel features of construction and combinations and arrangements of parts as will be more fully hereinafter described and pointed out in the claims.

In the accompanying drawings:

Figure 1 is a view in front elevation of my improved machine;

Figure 2 is a view in vertical section therethrough;

Figure 3 is a top plan view thereof;

Figure 4 is a fragmentary view similar to Figure 3, showing the manner of use of my improved shim punching attachment; and

Figure 5 is a view partly in elevation and partly in section of the punching attachment.

Referring in detail to the drawings, I have indicated at 1, a hollow column or platform supported upon a base 2, which comprises a socket 3, receiving and holding the lower end of the column and a plurality of legs supporting the socket and integral therewith. A platform 4 is integral with a split sleeve 5 which is slidably mounted

upon the platform, and which may be tightened by certain securing devices such as 6, to lock the sleeve and platform against vertical sliding movement on the standard. The platform is provided with the usual strengthening webs 7.

A substantially U-shaped yoke 8 is likewise connected to a split sleeve 9 slidably mounted upon the standard above the platform 4 and capable of being locked in any desirable position upon the standard. The yoke 8 is preferably connected by a forwardly extending web 10 to the sleeve 9. The ends of the yoke provide mounting for a transverse shaft 11 of angular cross section. A lever 12 is pivotally connected at one end to a bracket 13 fixed upon the intermediate portion of the yoke 8. A tie rod 14 connects the intermediate portion of the lever 12 with a lever 15, which has one end mounted in one of the legs of the base 2, as indicated at 16. The free end of the lever 15 is provided with a pedal 17 so that depression of the pedal operates through the medium of the tie rod 14 to depress the lever 12.

A plurality of compressing arms 18 are carried by the shaft 11 and are operable upon turning of the shaft to compress valve springs located on the platform. These arms include bifurcated forward ends 19 adapted to conveniently engage with the conventional type of valve. Turning of the shaft 11 is effected by a crank arm 20 fixed to the shaft and a depending hooked link 21 at the end of the crank arm which engages under a hooked lug 22 fixed to the upper face of the lever 12.

A cross pin 23 mounted in an opening in the web 10 may be selectively engaged by any of the notches 24 in a depending locking arm 25 pivoted to the lever 12.

The manner of use of the machine is as follows: Any suitable number of valve springs are positioned upon the platform or table 4 under the free ends of the arms 18. Depression of the pedal 17 will operate through the connecting means above described to depress the lever 12. This lever in turn transmits power through the link 21 and the crank arm 20, to turn the shaft 11 and positively move the free ends of the arms 18 downwardly toward the platform 4, thus compressing the springs to make possible the disassembling or repair of the valves on the table. The valve

springs may be held in compressed position by merely swinging the locking member 25 into engagement with the cross pin 23 to hold the lever 12 against upward movement. In order to release the springs it is merely necessary to press lightly upon the foot pedal permitting the locking member 25 to swing back to its normal position and the action of the springs to restore 10 the arms and levers to their normal positions.

It will be apparent that this machine might be conveniently adapted for use in connection with an ordinary work bench by 15 simply shortening the column, providing the opening in the bench through which the column may pass and using either the platform 4 or the bench itself to work upon.

It has been heretofore suggested that the 20 machine might be used for punching shims as well as for compressing valve springs. In this connection, attention is called to Figures 3, 4 and 5 of the drawings, wherein it will be seen that I provide a block 26 having a central opening therethrough and having a plurality of spring held plungers 27 of various sizes mounted in the upper portion of the block and extending into the opening. The movement of these plungers 25 may be limited by cross pins 28 carried thereby. Openings 29 in the lower portion of the block register with the plungers. Studs 30 are fixed to the under face of the block 26 and are adapted to selectively 30 register with and fit within any of a transverse series of openings 31 in the platform 4, in accordance with the plunger 27 which it is desired to depress. In other words, the studs and openings permit transverse adjustment of the block 30. When the block 40 is in place, the lever arm 12 will operate upon any one of the plungers 27 to depress the same, it of course being understood that the shims are interposed between the lower 45 ends of the plungers and the openings 29 so that descent of the plungers will punch the shims.

Although I have illustrated one of the 50 preferred embodiments of my invention, it will be evident that various slight changes and alterations might be made in the general form and arrangement of the parts described without departing from the invention, and hence I do not wish to limit myself 55 to the precise details set forth, but shall consider myself at liberty to make such slight changes and alterations as fairly fall within the spirit and scope of the appended claims.

I claim:

1. In a machine of the class described, a 60 platform, a plurality of pivotally mounted valve compressing arms adapted to co-operate with the platform to compress valve springs, and pedal operated means for depressing the free ends of the arms.

2. In a machine of the class described, a platform, a plurality of pivotally mounted valve compressing arms adapted to co-operate with the platform to compress valve springs, pedal operated means for depressing the free ends of the arms, and means for locking the arms in depressed position. 70

3. In a machine of the class described, a hollow standard, a vertically adjustable platform on the standard, a vertically adjustable yoke carried by the standard, a shaft journaled in the arms of the yoke, a plurality of compressing arms fixed to the shaft and extending over the platform, and means for turning the shaft to depress the 80 free ends of the arms. 75

4. In a machine of the class described, a hollow standard, a vertically adjustable platform on the standard, a vertically adjustable yoke carried by the standard, a shaft 85 journaled in the arms of the yoke, a plurality of compressing arms fixed to the shaft and extending over the platform, means for turning the shaft to depress the free ends of the arms, and said arms including bifurcated free ends adapted to engage with a valve. 90

5. In a machine of the class described, a hollow standard, a vertically adjustable platform on the standard, a vertically adjustable yoke carried by the standard, a shaft journaled in the arms of the yoke, a plurality of compressing arms fixed to the shaft and extending over the platform, means for turning the shaft to depress the free ends 100 of the arms, said arms including bifurcated free ends adapted to engage with a valve, said means including a lever fulcruming on the yoke, a crank arm fixed to the shaft, and a hooked link carried by the crank arm engageable with the lever, and means for depressing the lever. 105

6. In a machine of the class described, a hollow standard, a vertically adjustable platform on the standard, a vertically adjustable 110 yoke carried by the standard, a shaft journaled in the arms of the yoke, a plurality of compressing arms fixed to the shaft and extending over the platform, means for turning the shaft to depress the free ends of 115 the arms, said arms including bifurcated free ends adapted to engage with a valve, said means including a lever fulcruming on the yoke, a crank arm fixed to the shaft, a hooked link carried by the crank arm engageable with the lever, means for depressing the lever, said last-mentioned means compressing a pedal operated lever at the base of the column, and a tie rod connecting the two levers. 120

7. In a machine of the class described, a hollow standard, a vertically adjustable platform on the standard, a vertically adjustable yoke carried by the standard, a shaft journaled in the arms of the yoke, a 125 130

- plurality of compressing arms fixed to the shaft and extending over the platform, means for turning the shaft to depress the free ends of the arms, said arms including 5 bifurcated free ends adapted to engage with a valve, said means including a lever fulcruming on the yoke, a crank arm fixed to the shaft, a hooked link carried by the crank arm engageable with the lever, means 10 for depressing the lever, said last-mentioned means compressing a pedal operated lever at the base of the column, a tie rod connecting the two levers, and means for locking the levers in depressed position.
- 15 8. In a machine of the class described, a hollow standard, a vertically adjustable platform on the standard, a vertically adjustable yoke carried by the standard, a shaft journaled in the arms of the yoke, a plurality of compressing arms fixed to the shaft and extending over the platform, means for turning the shaft to depress the free ends of the arms, said arms including 20 bifurcated free ends adapted to engage with a valve, said means including a lever fulcruming on the yoke, a crank arm fixed to the shaft, a hooked link carried by the crank arm engageable with the lever, means 25 for depressing the lever, said last-mentioned means compressing a pedal operated lever at the base of the column, a tie rod connecting the two levers, a notched locking member carried by the first-mentioned lever, and a pin carried by the yoke adapted to 30 be engaged by said locking member to hold the lever in depressed position.
- 35 9. In a machine of the class described, a support, a platform mounted on the support, a shaft carried by the support, a plurality of compressing arms secured to the 40 shaft, and means for turning the shaft to depress the free ends of said arms.
10. In a machine of the class described, a support, a platform mounted on the support, a yoke mounted on the support, a shaft 45 mounted in the yoke, a plurality of compressing arms on the shaft, means for turning the shaft to depress the free ends of the arms, and means for locking the arms depressed. 50
11. In a machine of the class described, a platform, a hollow block supported on the platform and adjustable transversely thereof, a plurality of spring held punchers mounted in the block, a compressing arm 55 adapted to selectively operate upon any of the punchers, and pedal operated means for depressing the arm.
12. In a machine of the class described, a support having a yoke-shaped member at 60 its upper end, a platform carried by the support adjacent its upper end, a lever pivotally mounted on the member, means for depressing the lever, a plurality of compressing arms pivotally mounted in the said 65 member, and means for connecting the arms with the lever to cause them to partake of the movement of said lever.
13. In a machine of the class described, a support having a yoke-shaped member at 70 its upper end, a platform carried by the support adjacent the upper end thereof, a lever mounted on the member, means for depressing the lever, a shaft mounted in the said member, a plurality of compressing arms 75 on the shaft, and a crank arm on the shaft and provided with a link having interlocking engagement with said lever.

GEORGE S. ROBERTS.
